UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR AN ARM FOR CHANDELIERS AND BRACKETS.

46,931.

Specification for Design.

Patented Feb. 9, 1915.

Application filed October 9, 1914. Serial No. 865,939. Term of patent 3½ years.

To all whom it may concern:

Be it known that I, CHARLES E. JONES, a citizen of the United States, residing at Chicago, in the county of Cook and State of Illinois, have invented a new, original, and ornamental Design for an Arm for Chandeliers and Brackets, of which the following is a specification, reference being had to the accompanying drawing, forming part thereof.

Figure 1, is a side elevation of an arm for

chandeliers and brackets, showing my new design. Fig. 2, is a top elevation of the same.

I claim:

The ornamental design for an arm for chandeliers and brackets, as shown.

CHARLES E. JONES.
